UNITED STATES PATENT OFFICE.

HARRY W. LYONS, OF TOWNSEND, MONTANA.

LOCK.

1,249,974.

Specification of Letters Patent. Patented Dec. 11, 1917.

Application filed June 12, 1917. Serial No. 174,279.

To all whom it may concern:

Be it known that I, HARRY W. LYONS, a citizen of the United States, residing at Townsend, in the county of Broadwater and State of Montana, have invented certain new and useful Improvements in Locks; and I do hereby declare the following to be a full, clear, and exact description of the invention, such as will enable others skilled 10 in the art to which it appertains to make and use the same.

This invention relates to improvements in a lock and has for one of its objects the provision of a device of this character, 15 whereby it is necessary to insert a coin within the lock before the same can be moved into a locked position.

Another object of this invention is the provision of a sliding bolt normally urged 20 outwardly of the casing of the lock and which is held in a retracted position by a locking member, which locking member is adapted to be actuated upon the insertion of a coin within the lock casing.

25 A further object of this invention is the provision of means carried by the locking or sliding bolt, which will prevent the key of the lock from being withdrawn from the casing after the sliding bolt has been re- 30 tracted, thus preventing loss of the key while the lock is in an unlocked position.

A still further object of this invention is the provision of a lock of the above stated character, which will be simple, durable, 35 and efficient, and which may be manufactured and sold at a comparatively low cost.

With these and other objects in view as will become more apparent as the description proceeds, the invention consists in certain 40 novel features of construction, combination and arrangement of parts as will be hereinafter more fully described and claimed.

For a complete understanding of my invention, reference is to be had to the following description and accompanying drawings, in which:—

Figure 1 is a longitudinal sectional view of a lock constructed in accordance with my 45 invention,

Fig. 2 is a transverse sectional view taken on the line 2—2 of Fig. 1, showing the means for preventing the key from being withdrawn from the casing when the lock 50 is in an unlocked position,

Fig. 3 is a fragmentary transverse sec-

tional view taken on the line 3—3 illustrating the means for supporting the locking member and the sliding bolt.

Referring in detail to the drawings, the 60 numeral 1 indicates a casing having the usual removable cover 2, which is secured to the casing by fasteners 3. The casing 1 is provided with an opening 4 in one end thereof to permit a sliding bolt 5 to extend 65 outwardly of the casing for engagement with the ordinary keeper, (not shown). The inner end of the sliding bolt 5 is provided with a slot 6 for the purpose of receiving the web portion of a substantially U- 70 shaped supporting member 7 that is secured to the casing as at 8. The sliding bolt 5 is provided with a longitudinally extending recess 9 in communication with the slot 6 for the purpose of receiving a coiled spring 10 75 that bears against the supporting member 7 for normally urging the sliding bolt 5 exteriorly of the casing and into engagement with the keeper (not shown). The sliding bolt 5 is provided with a recess 11, forming 80 a shoulder 12 to be engaged by wards 13 of a key 14. The key 14 is inserted into the casing by way of a key hole 15 and by rotating the same, the wards 13 engage the shoulder 12 and retract the bolt 5. 85

A locking member 16 is pivoted within one end of the casing as at 17 and extends longitudinally thereof and in close proximity to the sliding bolt 5 and has formed within its under face, a notch 18 for the 90 purpose of engaging a lug 19 formed upon the upper edge of the locking bolt 5 when said locking bolt 5 is moved into a retracted or unlocked position.

The locking member 16 is provided with 95 a slot 20 for the purpose of receiving the web portion of the substantially U-shaped supporting member 7, and which slot will permit said member to move upwardly and downwardly within the casing for the purpose of disengaging the notch or recess 18 from engagement with the lug 19 to free the sliding bolt 5. 100

Walls 21 are formed within the casing for the purpose of providing a coin passage 22, 105 which is provided with upper and lower vertical branches 23 and 24. The lower vertical branch 24 is offset from the upper vertical branch 23 by a horizontal branch 25. The casing 1 is provided with a coin receiving slot 26 in communication with the upper vertical branch 23 of the passage 22

- for permitting a coin to be deposited upon the horizontal wall 27 of the passage. A spring actuated plunger 28 is mounted within the casing and has formed upon its inner 5 end, a head 29 that is adapted to engage the coin as shown in Fig. 1 to move the same forwardly against the beveled end 30 of the locking member 16, which causes said locking member to move upwardly upon its 10 pivot 17 disengaging the recess 18 from the lug 19 so that the sliding bolt 5 may be moved exteriorly of the casing and into engagement with the keeper (not shown), under the influence of the spring 10. As the 15 locking member 16 moves upwardly to disengage the recess 18 from the lug 19, the coin drops downwardly within the lower vertical branch 22, which constitutes a coin receiving chamber.
- 20 A substantially L-shaped member 31 is secured to the sliding bolt 5 as shown at 32 and is adapted to have its horizontal portion 33 to extend through the wards 13 of the key 14, when the sliding bolt 5 is in a retracted position to prevent the key from being withdrawn from the casing, thus preventing the danger of losing the key while the lock is in an unlocked position.

While I have shown and described the 30 preferred embodiment of my invention, it will be understood that minor changes in construction, combination and arrangement of parts may be made without departing from the spirit and scope of the invention as 35 claimed.

Having thus described my invention, what I claim is:—

1. A lock comprising a casing, a sliding bolt in said casing and normally urged exteriorly thereof, a locking member pivoted

within said casing and having a recess therein, a lug formed on said bolt and received within the recess when in a retracted position, means for retracting said bolt, said locking member having its free end beveled, 45 walls formed within said casing to provide a coin passage, said coin passage consisting of upper and lower vertical flanges connected by a horizontal branch to receive a coin, and a spring actuated member slidable 50 in the casing and adapted to engage the coin to move the same against the beveled end of the locking member for swinging said member upon its pivot to disengage the recess thereof from the lug. 55

2. A lock comprising a casing, a sliding bolt in said casing and having a recess and slot in communication with each other, a substantially U-shaped member extending through a slot and secured to the casing, a 60 spring located within the recess and bearing against the U-shaped member to urge the bolt exteriorly of the casing, a locking member pivoted within said casing and having a slot to receive the substantially U-shaped 65 member, said locking member having a recess, a lug formed on the locking bolt and received within the recess when said bolt is in a retracted position, means for retracting said bolt, and means for moving a coin 70 against the locking member to rock the same on its pivot to free the recess thereof of the lug.

In testimony whereof I affix my signature in presence of two witnesses.

HARRY W. LYONS.
